H. B. RUGGLES.
KNOCKDOWN DISPLAY BOX.
APPLICATION FILED JULY 18, 1914.

1,188,492.

Patented June 27, 1916.

UNITED STATES PATENT OFFICE.

HENRY B. RUGGLES, OF PASADENA, CALIFORNIA, ASSIGNOR TO AMERICAN PRODUCTS COMPANY, OF PORTLAND, MAINE, A CORPORATION OF MAINE.

KNOCKDOWN DISPLAY-BOX.

1,188,492.

Specification of Letters Patent. Patented June 27, 1916.

Original application filed January 2, 1914, Serial No. 809,896. Divided and this application filed July 18, 1914. Serial No. 851,708.

To all whom it may concern:

Be it known that I, HENRY B. RUGGLES, a citizen of the United States, residing at Pasadena, in the county of Los Angeles and 5 State of California, have invented certain new and useful Improvements in Knock-down Display-Boxes, of which the following is a specification.

This invention pertains to improvements 10 in box construction, and more especially to display boxes of the knock-down or collapsible type, and similar to that disclosed in my co-pending application for United States Letters Patent filed January 2, 1914, 15 Serial No. 809,896, whereof this application is a division.

It is the object of my invention to produce a collapsible box from a combination of fiber or pulp-board and wood members, or 20 from all-fibrous material; the provision of means whereby the parts may be quickly assembled either by the box manufacturer or by the user of the boxes; and a construction by which a box used in transporting 25 goods may be converted into a container adapted to display the contents.

In the accompanying drawings I have illustrated a preferred embodiment of my invention in the following views:—

30 Figure 1 is a perspective view of a display box made according to my invention; Fig. 2 is a fragmentary perspective view of an upper corner of my improved box; Fig. 3 is an enlarged sectional view of the construction shown in Fig. 2 with a different form of cover member designed to protect the transparent member.

Referring to the details of my invention, the reference characters 6 and 7 represent 40 respectively, the upper and lower frames which form the rims of the top and bottom of my improved box, to which frames or rims are fitted the side wall members 8 which are reinforced where bent to provide 45 corners, by strips of fabric or other suitable material, as indicated by the reference character 9 in Fig. 1. Fitted within the frame 6 is shown a supplemental lock or inner frame 10, the outer walls of which are 50 fitted to the inner walls of the frame 6.

As shown in the drawings, 12 represents a sheet of glass, mica, or other transparent material, the edges of which are secured to

the lower face of the supplemental frame 10.

13, represents a sheet of pulp or fibrous material which, as shown in Fig. 2, is secured to the under side of the outer frame 6, nails being used to attach said member 13 to said frame 6.

As shown in Figs. 2 and 3, suitable kerfs 6^b are formed in the underside of frame member 6, and these kerfs are preferably formed tapering outwardly from their bottoms with the mouth rounded as shown at 6^c; Fig. 2, such an enlarged mouth and tapering wall kerf facilitating the entrance of the margins of the side walls 8. The side walls 8 are preferably formed with apertures 8^a along their edges which receive the 70 glue or other adhesive which is placed in the kerfs 6^b in sufficient quantities so that when the margins of the walls 8 are pushed into said kerfs the sealing adhesive substance will flow into the openings 8^a and form, 75 when set or hardened, an efficient anchoring means for holding said side walls securely in place relative to the frame members 6 and 7. The cover member 13 is preferably 80 provided with a score line 13^a at the inner margin of the frame member 6, so as to facilitate the severance of a portion of the member lying within the frame when it is desired to open the box.

I prefer to make the interfitting walls of 85 the top members 6 and 10, and the corresponding members 7 and 11, in the bottom frame, with broken joints as indicated at 6^a, 10^a and 7^a, 11^a, that are preferably inclined or beveled about half their height 90 and are then stepped or provided with slight shoulders α and α' , respectively, that terminate in straight vertical walls y and y' , substantially as shown. The interfitting walls of the bottom frame are similarly inclined 95 and provided with shoulders X and X' and with straight walls Y and Y' . The members 10 are preferably secured to the members 6 by light nails which may be easily removed when it is desired to disconnect the two frames. This operation is resorted to when the user of the box wishes to convert it into a display container which is readily done by cutting out the portion of the cover 13 within the scored lines 13^a, 100 and then replacing the frame 10 with its

transparent member 12. When thus replaced the frame 10 will rest removably upon the frame 6, the shoulders α and α' serving as an effective support for the inner frame. When it is desired to protect the transparent member 12 in the shipment of the box supplied with such member, I will use a sheet of fiber 15 the margins of which will be bent up at right angles as at 15^a, 5 Fig. 3, and the same nails which secure the frame 10 to the frame 6 will pass through said flanges and hold the member 15 in place until the box reaches the hands of the user when the member 15 may be readily 15 removed by withdrawing the nails. In such case I may dispense with the cover member 13 on the under side of the transparent member 12.

From the construction illustrated and 20 above described, it will be obvious that I have provided a display container the members of which can be completely formed at a central manufacturing plant, can be shipped to the user who can assemble the parts 25 quickly and easily with the use of but few nails or brads, and who can lock the top and bottom members to the sides by merely pouring a suitable adhesive substance into the kerfs formed in the top and bottom 30 frames, and that when the box thus assembled is packed or filled any attempt to open it will require either the severance of the top or bottom walls 13, 14, from their respective frames or the fracture of the 35 hard sealing medium used in the kerfs and portions of which, as we have seen, will fill the apertures 8^a, thus disclosing that the package has been tampered with. It will also be observed that the receptacle may 40 readily be converted into a display box by the purchaser by removing the frame 10 having the transparent plate 12 and severing the member 13 along the scored lines 13^a whereupon the frame may be replaced and 45 is adapted to close the box. When a protecting member 15 is employed all that it is necessary to do is to remove the nails that secured said member 15 and frame 10 thus releasing the former and permitting 50 the same to be freely raised when access is desired to the interior of the receptacle.

While I have shown and described a rectangular box or container constructed according to my invention, it will be obvious 55 that all of the features thus shown and described are equally applicable to a cylindrical or other shaped container; hence I do not wish to be understood as limiting my invention to a rectangular box as the shape

is no part of my invention. The corner 60 strips may be flexible so that the sides can lie flat when not assembled with the cover members, or they may be of such material as to make a rigid structure at the corners. In this connection I have shown the members 9 as a thin flexible material pasted to the side members 8 and serving merely as 65 flexible hinges for said members.

Having thus described my invention what I claim is:

1. A display container comprising top and bottom frames, side and end walls secured to said frames, opaque top and bottom walls secured to the lower side of the top frame and the upper side of the lower frame, 75 a supplemental frame fitting within, supported by and detachably secured to said top frame, and a transparent sheet secured to said supplemental frame and lying contiguous to the opaque top wall. 80

2. A display container comprising a top frame, a portion of which is inclined and provided with a shoulder, a bottom frame, and side walls secured to said frames, a supplemental frame having its edge undercut 85 and provided with a shoulder and adapted to fit within and be removably secured to said top frame, a transparent sheet secured to said supplemental frame, and an opaque sheet lying adjacent thereto and adapted 90 to protect said transparent sheet.

3. A display container comprising a top frame, a bottom frame, and side walls secured to said frames, a supplemental frame fitting within and detachably secured to 95 said top frame, an opaque sheet secured to the underside of said top frame and provided with scoring substantially parallel to the edge of said frame, and a transparent sheet secured to said supplemental frame. 100

4. A display container comprising a top frame, a bottom frame, and side walls secured to said frames, a supplemental frame fitting within and detachably secured to 105 said top frame, an opaque sheet secured to the underside of said top frame and provided with scoring substantially parallel to the edge of said frame, and a transparent sheet secured to the underside of said supplemental frame and overlying said opaque 110 sheet.

In testimony whereof I affix my signature in the presence of two witnesses.

HENRY B. RUGGLES.
